UNITED STATES PATENT OFFICE.

CHARLES M. STEIN, OF PARIS, FRANCE, ASSIGNOR TO SOCIETE ANONYME DES APPAREILS DE MANUTENTION ET FOURS STEIN, OF PARIS, FRANCE, A CORPORATION OF FRANCE.

SPELTER FURNACE.

Application filed August 19, 1921. Serial No. 493,598.

To all whom it may concern:

Be it known that I, CHARLES M. STEIN, a citizen of France, residing at Paris, France, have invented a certain new and useful Spelter Furnace, of which the following is a specification.

The invention has for an object to provide a furnace adapted for use for heating spelter or like material, wherein substantial uniformity of temperature will be maintained throughout the various parts of the furnace, and the heat thus evenly distributed to the material contained therein.

Another object of the invention is to construct a furnace of the above character in such manner that a relatively high heating efficiency will be secured particularly on account of the manner in which the heated gases are led to the material to be heated.

Another object is to provide a furnace of the above character wherein a recuperator is so associated with the remainder of the apparatus as to form a compact and efficient structure in which the flow of adequately pre-heated air for combustion purposes will be promoted. The furnace also embodies special features designed to prevent the parting or choking of the recuperator due to the dust and slag carried along with the spent gases issuing from the combustion chamber.

Further objects and advantages of the invention will be in part obvious and in part specifically pointed out in the description hereinafter contained which, taken in connection with the accompanying drawings, discloses a preferred embodiment of the invention; such embodiment, however, is to be considered merely as illustrative of its principle. In the drawings:

Fig. 1 is a vertical transverse sectional view of a furnace made in accordance with the invention.

Fig. 2 is a longitudinal vertical section taken on line 2—2 of Fig. 1, certain parts of the structure being cut away to show a preferred section on line 2—2 of Fig. 1.

The illustrated embodiment of the invention is shown in the form of a spelter furnace adapted to receive spelter containing retorts upon inclined shelves 1 located in the walls of a chamber 2, which thus contains the material to be heated. It will be understood that the retorts are suitably spaced apart to permit the flow of heated gases past the same.

If a furnace of the reversing type be employed for purposes similar to those above-mentioned, or a furnace working on the recuperative principle, there is a tendency towards irregular heating of the retorts, due to the fact that the parts of the chamber into which the heated gases enter tend to become much hotter than the remainder thereof, resulting in an undue breakage of retorts. According to the present invention the hot gases of combustion are led from the combustion chamber 3 to the chamber 2 in a downward direction, the combustion chamber 3 in the present instance being located above chamber 2, and extending directly over the top thereof. Thus as the heated gases pass from combustion chamber 3 downward to chamber 2, if a certain portion of the chamber 2 tends to become unduly hot, the gases at the corresponding point will be hotter, and will tend to rise or move downward less slowly than gases passing through the portions of the chamber 2 which are at a lower temperature, and an equalization of temperature will be brought about. This equalization of temperature results from the faster flow of gases past portions of chamber 2 which tend to remain at a relatively lower temperature, and at the same time the heat of the gases of combustion is effectively utilized, since the portions of the gases at a higher temperature tend to rise and thus remain in chamber 2 until their heat has become fully transferred to the material to be heated.

It is preferred to lead the air and combustible gas to combustion chamber 3 in an upward direction, whereby the flow of the gas is reversed in passing into chamber 2. According to the present form of the invention, a pair of heating chambers 2 are disposed side by side and separated by a wall 4 of the furnace, the combustion chamber 3 being made large enough to extend over the top of both the heating chambers. The air and combustible gas are then led into the bottom of chamber 3 respectively by means of upwardly-directed air conduits 5 contained within the furnace wall 4, and similar combustible gas conduits 6 alternating with the air conduits. (See upper right hand portion of Fig. 2). A plurality of mixing chambers 7 separated by partitions 8 may be interposed between conduits 5—6 and the combustion chamber 3 in such manner that combustion

of the mixed air and gas begins within the chambers 7, and is completed within the combustion chamber 3. Thus the gases of combustion are projected upwardly and centrally thereof, and the current of gas then divides and passes downwardly through the chamber 2, with the result that the retorts, particularly at the upper end of such chamber, are not subjected to the direct action of 10 burning gases, a factor which tends to avoid undue localized heating.

As shown in Fig. 1, the combustible gas may be led into the furnace through a conduit 9, which is in communication with a gas distributing chamber 10 extending longitudinally of the furnace, and located beneath the conduits 5 and 6. In order to regulate the flow of combustible gas into the different 15 portions of the distributing chamber 10, a plurality of ports 11 may be interposed between chamber 10 and the supply of gas, suitable dampers such as slab 12 being associated with the ports, and being adjustable from the exterior of the furnace to obtain 20 an even flow of gas throughout the length of the furnace.

I prefer to preheat the incoming air for the furnace by means of a recuperator, which may be combined with the air conduits 5 in such manner as to secure a substantially unimpeded upward flow of the air to the combustion chamber 3. As shown, the recuperator comprises a plurality of vertical tiers of blocks or tiling 13, each tile 35 having a plurality of unimpeded vertical air passages 14 registering similar passages in the tile immediately above and below the same, whereby air may enter through the immediate conduits underneath the recuperator, and pass upwardly through the unimpeded vertical passages 14 to an air distributing chamber 16, which communicates 40 with the air conduits 5.

In order to insure that the flow of gases 45 of combustion downward through chamber 2 will produce a uniform degree of heat throughout the different portions of the chamber, such gases are led through a plurality of outward ports 17 extending from 50 the bottom wall of the chamber into gathering flues 18 respectively extending longitudinally of the chamber, and suitable dampers such as the slabs 19 are provided 55 with ports 17, the dampers being adjustable from the exterior of the furnace to regulate 60 the flow of gases through the several ports 17. Ordinarily the end dampers 19 will be open somewhat further than the intermediate ones, since the end portions of the furnace tend to be the coolest.

The spent gases are passed through the recuperator, the tiles 13 supporting between them a plurality of plates 20 which provide horizontal passageways 21 to receive the spent gases. As shown in Fig. 2,

the spent gases pass alternatively through the upper two sets of passages 21 from right to left to a gathering chamber 22 at the end of the recuperator. This chamber is provided with a partition 23, having an opening 24 therein, the extent of which is controlled by the adjustable slab 25. The spent gases then pass from left to right through the two lower sets of passageways 21, and thence to the exhaust flue 26. Thus the 75 damper or slab 25 regulates the flow of the

gases of combustion as a whole, while the dampers 19 serve to control the flow of gases through the several portions of the heating chamber 2.

In furnaces of the character described, the tiles or checker work of the recuperator or régénérator are liable to clog up quickly on account of the slag and dust carried off into the recuperator along with the spent 85 gases, and it is oftentimes difficult to remove the dust and slag from the tiles or checker work without disabling the furnace for a substantial period of time. In connection with the present furnace I interpose a dust or slag trap 27 between the gathering flue 18 and each recuperator, whereby the gases after leaving flue 18 pass downwardly under a partition 28 and over a ledge 29 before entering passageways 21, thus depositing the 95 major portion of the slag or dust in the trap 27, from which it may be easily cleaned through the normally closed opening 30 associated therewith.

The several parts of the furnace structure are so related to each other that the flow of incoming air and combustible gas through the combustion chamber 3 is substantially unobstructed by the parts of the structure which accommodate the spent gases, and yet the furnace as a whole is relatively compact, substantially all of the space within its confines being utilized.

While a specific form of the invention has been described, it is obvious that many changes may be made therein without departing from the spirit of the invention as defined in the following claims.

I claim:

1. A non-reversing furnace of the class described having a chamber adapted to contain material to be heated, said chamber being constructed to permit the downward flow of heated gases therethrough, a combustion chamber located substantially entirely above said first-mentioned chamber and communicating therewith, and means for leading combustible gas to said combustion chamber, whereby the gas will pass from said combustion chamber through said first-mentioned chamber in a downward direction.

2. A non-reversing furnace of the class described having a chamber adapted to contain material to be heated, said chamber be-

ing constructed to permit the downward flow of heated gases therethrough, a combustion chamber associated with said first-mentioned chamber and communicating therewith, and means for projecting substantially all combustible gas into said combustion chamber in an upward direction, and leading the gas from said combustion chamber into and through said first-mentioned chamber in a downward direction.

3. A non-reversing furnace of the class described having a chamber adapted to contain material to be heated, said chamber being constructed to permit the downward flow of heated gas therethrough, a combustion chamber located substantially entirely above said first-mentioned chamber and communicating with the upper portion thereof, and means for projecting combustible gas into said combustion chamber in an upward direction whereby the flow of gas is reversed in the combustion chamber and the gas flows downwardly therefrom through said first-mentioned chamber.

25 4. A non-reversing furnace of the class described having a chamber adapted to contain material to be heated, said chamber being constructed to permit the downward flow of heated gas therethrough, a combustion chamber associated with said first-mentioned chamber and communicating only with the upper portion thereof, and means for leading combustible gas to said combustion chamber and then down through said first-mentioned chamber.

5. A non-reversing furnace of the class described having chambers disposed side by side and adapted to contain material to be heated, said chambers being constructed to permit the downward flow of heated gases therethrough, a combustion chamber communicating only with the upper portions of both of said first-mentioned chambers, and means for leading combustible gas into said combustion chamber whereby the gas will divide in said combustion chamber and pass through both of said first-mentioned chambers in a downward direction.

6. A non-reversing furnace of the class described having chambers disposed side by side and adapted to contain material to be heated, said chambers being constructed to permit the downward flow of heated gases therethrough, a combustion chamber extending over the space above both of said first-mentioned chambers and communicating only with the upper portions of such chambers, and means for projecting combustible gas into said combustion chamber in an upward direction, whereby the flow of gas is reversed in the combustion chamber and the gas divides and passes through both of said first-mentioned chambers in a downward direction.

65 7. A non-reversing furnace of the class

described comprising chambers disposed side by side and adapted to contain material to be heated, said chambers being constructed to permit the downward flow of heated gases therethrough, a combustion chamber located above said first-mentioned chambers, and means comprising upwardly directed conduits disposed between said first-mentioned chambers for leading combustible gas to said combustion chamber.

8. A furnace of the class described comprising chambers disposed side by side and adapted to contain material to be heated, said chambers being constructed to permit the downward flow of heated gases therethrough, a combustion chamber located above said first-mentioned chambers, and means comprising separate upwardly directed air and combustible gas conduits disposed between said first-mentioned chambers for leading combustible gases to the combustion chamber.

9. A furnace of the class described comprising members disposed side by side and adapted to contain material to be heated, said chambers being constructed to permit the downward flow of heated gas therethrough, a combustion chamber located above said first-mentioned chambers, and means comprising upwardly directed air and combustible gas conduits located in the wall between said first-mentioned chambers, and a mixing chamber common to said air and gas conduits interposed between the same and the combustion chamber.

10. A furnace of the class described having a chamber adapted to contain material to be heated and constructed to permit the downward flow of heated gases therethrough, said chamber being provided with outlet ports adjacent its bottom to permit the downward flow of heated gas through all portions of the chamber, and means to regulate the rate of downward flow of gas in different portions along the length of the chamber.

11. A furnace of the class described having a chamber adapted to contain material to be heated and constructed to permit the downward flow of heated gas therethrough, said chamber being provided with outlet ports adjacent its bottom to permit the downward flow of heated gas through all portions of the chamber, and means to regulate the rate of downward flow of gas from different portions along the length of the chamber, said means comprising dampers respectively associated with said outlet ports.

12. A furnace of the class described having a chamber adapted to contain material to be heated and constructed to permit the downward flow of heated gases therethrough, said chamber being provided with outlet ports adjacent its bottom to permit

the downward flow of heated gas through all portions of the chamber, means to regulate the rate of downward flow of gas from different portions along the length of the chamber, and a gathering flue associated with said chamber, and into which said above-mentioned outlet ports all lead.

13. A furnace of the class described comprising a chamber adapted to contain material to be heated and constructed to permit the downward flow of heated gas therethrough, outlet ports being provided adjacent the bottom of said chamber, a gathering flue underlying said outlet ports, and a recuperator located beneath said gathering flue adapted to receive the gas passing therefrom, a slag trap being interposed between said gathering flue and said recuperator.

14. A furnace of the class described comprising a combustion chamber, means for leading air to said chamber comprising upwardly-directed air conduits located beneath the same, and means for preheating the air passing into said conduits comprising a recuperator disposed beneath the same and having substantially unimpeded vertical air passages therein, communicating with said air conduits.

15. A furnace of the class described comprising chambers disposed side by side and each adapted to contain material to be heated, a combustion chamber extending over the space above both of said first-mentioned chambers, means for leading air to said combustion chamber in an upward direction, comprising upwardly directed air conduits located in the wall of the furnace between said first-mentioned chambers and means for preheating the air entering said conduits comprising recuperators disposed respectively beneath said first-mentioned chambers and on opposite sides of said conduits, said recuperators having substantially unimpeded vertical air passages in communication with said air conduits.

16. A furnace of the class described comprising chambers disposed side by side and each adapted to contain material to be heated, a combustion chamber extending over the space above both of said first-mentioned chambers, means for leading air to said combustion chamber in an upward direction, comprising upwardly-directed air conduits located in the wall of the furnace between said first-mentioned chambers, and means

for preheating the air entering said conduits comprising recuperators disposed respectively beneath said first-mentioned chambers and on opposite sides of said conduits, said recuperators having substantially unimpeded air passages in communication with said air conduits, the wall of the furnace between said first-mentioned chambers being provided with combustible gas conduits alternating with said air conduits.

17. A furnace of the class described comprising chambers disposed side by side and each adapted to contain material to be heated, a combustion chamber extending over the space above both of said first-mentioned chambers, means for leading air to said combustion chamber in an upward direction, comprising upwardly-directed air conduits located in the wall of the furnace between said first-mentioned chambers, and means for preheating the air entering said conduits comprising recuperators disposed respectively beneath said first-mentioned chambers and on opposite sides of said conduits, said recuperators having substantially unimpeded air passages in communication with said air conduits, the wall of the furnace between said first-mentioned chambers being provided with combustible gas conduits alternating with said air conduits.

18. A furnace of the class described comprising chambers disposed side by side and each adapted to contain material to be heated, a combustion chamber extending over the space above said first-mentioned chambers, recuperators located respectively under the chambers, air conduits between the chambers and leading from said recuperators toward the combustion chamber, gathering flues for receiving the spent gases passing from the first-mentioned chambers disposed underneath said chambers and interposed between the same and said recuperators.

19. The combination set forth in claim 18, together with slag traps located beneath the gathering flues and beyond the ends of the recuperators.

In testimony that I claim the foregoing, I have hereunto set my hand this 12 day of July, 1921.

CHARLES M. STEIN.
